BUILDING

Bobby G. Choate, Texarkana, Tex., assignor to Space Foods, Inc., Texarkana, Tex., a corporation of Texas

Filed Apr. 25, 1969, Ser. No. 16,899

Term of patent 14 years

Int. Cl. D25—04

U.S. Cl. D13—1

Fig. 1

Fig. 2

Fig. 3

FIG. 1 is a side elevational view of a building embodying my new design (the appearance of the building is identical as seen in front, rear, left side and right side elevational views);

FIG. 2 is a top view thereof; and

FIG. 3 is a bottom view thereof.

I claim:

The ornamental design for the building, as shown and described.
